UNITED STATES PATENT OFFICE.

FRANK H. WARREN, OF SWAMPSCOTT, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

TRIMMING-MACHINE.

1,271,638.

Specification of Letters Patent.

Patented July 9, 1918.

Application filed November 6, 1915. Serial No. 60,116.

To all whom it may concern:

Be it known that I, FRANK H. WARREN, a citizen of the United States, residing at Swampscott, in the county of Essex and 5 State of Massachusetts, have invented certain Improvements in Trimming-Machines, of which the following description, in connection with the accompanying drawings, is a specification, like reference characters on 10 the drawings indicating like parts in the several figures.

This invention relates to trimming machines for use in the manufacture of boots and shoes and particularly to machines for 15 trimming or randing the upper surface of the sole or welt of a shoe adjacent to its edge. The invention is herein shown as embodied in a machine particularly adapted for operating upon portions of the stock at 20 or adjacent to the heel seat, but it should be understood that the invention is not thus restricted in its application and that machines embodying the novel features of the invention may likewise be used upon other 25 portions of the sole or welt.

In the operation of trimming heels, particularly upon the better grades of shoes, it is the usual practice first to trim around the side of the heel from one breast corner 30 to the other and then to subject the heel portion of the shoe to the operation of a finishing cutter which simultaneously bevels or rands the upper surface of the sole around the heel seat and operates upon the edge of 35 the sole or portions of the heel adjacent to the heel seat so as to leave a sharply defined edge at the margin of the heel seat. For the best results it is found to be advantageous, prior to the operation of the final 40 randing or finishing cutter, to make a cut along the margin of the upper surface of the sole so as to provide a more open crease between the sole and the upper for the admission of the randing cutter. This operation 45 it has been the usual practice heretofore to perform by the use of a hand tool.

It is an important object of this invention to provide a machine for use in performing the above described preliminary randing op-

eration upon a shoe. To this end an important feature of the invention consists in the combination with a cutter suitably formed for operating upon the margin of a sole at the heel seat, of a novel construction and arrangement of mechanism for guiding the shoe as the latter is presented to the cutter and for protecting the upper from injury during the trimming operation. The construction herein shown includes, in combination with the cutter, a shield arranged for 50 engagement in the rand crease to protect the upper from contact with the cutter and determine the position of the shoe longitudinally of the cutter axis, and means for protecting the surface of the upper from injury 55 through rubbing contact with the shield. In the construction shown the upper protecting means serves also as a guide to determine the inward extent or depth of the cut as well as to limit the extent of projection of the 60 shield into the rand crease; and in order to insure that the upper shall not be injured by rubbing contact with the guide, as well as to facilitate the turning of the shoe, the 65 guide in this construction comprises a wheel 70 arranged to be turned by contact with the shoe.

It is a further important object of this invention to provide means suitable for use in the shank of a welt shoe for trimming the end of the welt so as to aline the crease in the shank with the rand crease at the heel seat. Since the crease is deeper in the shank than it is around the heel, it is desirable 80 in performing this operation at the welt end 85 to trim farther inward or deeper in the crease than when trimming around the heel seat. This invention accordingly provides an upper engaging guide arranged to yield relatively to the cutter to permit the depth 90 of the cut to be varied either for trimming in the shank or in case it is desired to make a deeper cut than usual at other portions of the sole, and this arrangement constitutes a further important feature of the invention. 95

The above and other features of the invention, including certain details of construction and combinations of parts, will

now be described with reference to the accompanying drawings and pointed out in the claims.

In the drawings:

5 Figure 1 is a view in front elevation of the head portion of a machine in which the invention is embodied,

10 Fig. 2 is a plan view of a portion of the mechanism shown in Fig. 1 detached,

15 Fig. 3 is a view of a portion of the mechanism in side elevation, and

20 Fig. 4 is a view in section on the line 4—4 of Fig. 3.

25 Mounted for rotation in bearings in the frame 2 of the machine is a shaft 4 to the outer end of which is secured by means of a screw 6 a cutter 8, this cutter having a beveled or conical end face next to the shaft provided with cutting edges adapted for 30 randing the heel seat of a shoe or for beveling or randing other portions of the projecting margin of the sole or welt. Mounted upon the frame above the shaft is a bracket 10 to the outer end of which is secured a 35 shield 12 in one side of which, as shown by dotted lines in Fig. 4, is formed a slight depression to receive the larger end of the cutter 8 and a central recess to receive the head of the screw 6. The lower end of the shield, 40 as shown in Fig. 4, is curved in substantially concentric relation to the axis of the cutter, and is thus adapted to enter freely any portion of the crease between the upper and the sole of a shoe so as to determine the position of the shoe longitudinally of the axis 45 of the cutter and protect the upper from contact with the cutter. The bracket 10 should be so adjusted as to position the shield in very close relation to the cutter, 50 and to this end the bracket is provided with a slot 14 to permit it to be adjusted longitudinally relatively to a clamping screw 16 which is threaded in the frame 2. In order to maintain the bracket in parallel relation 55 to the shaft 4 in all positions of its adjustment, so as to insure that the shield 12 shall be positioned in parallel relation to the end of the cutter, the frame 2 is provided with a slideway 18 in which the bracket is 60 mounted. Accurate adjustment of the bracket may be effected by means of a screw 20, one end of which is seated in a bearing 22 on the frame while the other end is threaded for engagement in a threaded bore 24 in the bracket. After the bracket has 65 been adjusted by means of the screw 20, it may be retained in adjusted position by tightening the screw 16. A set screw 26 is arranged to engage the screw 20 to afford additional security against change in the adjustment.

Secured by means of screws 28 to the outer end of the bracket 10, in such manner as to clamp the shield 12 in place, is a plate 30 65 provided with a guideway in which a slide

32 is vertically movable. The plate 30 and the shield 12 are further maintained in their proper positions on the bracket 10 by plates 33 secured to the sides of the bracket and overlapping the edges of the plate 30 and the shield. Mounted upon the lower end of the slide 32 is a wheel 34 the hub portion of which, as shown in Fig. 4, has a bearing in the slide and is formed with a threaded bore to receive a screw 36 which serves to retain the wheel in position. The wheel 34 has a transverse peripheral contour approximating the vertical contour of the upper of a shoe adjacent to the rand crease, and the wheel is of such diameter that when in its normal position, illustrated in Figs. 3 and 4, in which it is substantially concentric with the cutter 8 and with the curve on the lower end of the shield 12, its outer edge is closely adjacent to all portions of the curved edge of the shield. The radius of the wheel in the construction shown, therefore, is substantially equal in length to the radius of the curve of the shield 12. The slide 32 is provided with a slot 38 to permit it to move vertically relatively to the screws 28, and the upper screw 28 serves by engagement with the slide at the end of the slot to determine the limit of downward movement of the slide. The slide is yieldingly maintained at its lower limit of movement by means of a spring 40 positioned in a socket in a lug 42 on the bracket 10 and bearing at its upper end against a screw 44 whereby its tension may be adjusted.

100 In using the machine above described to perform the preliminary trimming operation around the heel seat prior to the operation of the final randing or finishing cutter, the shoe is positioned as shown in Fig. 1 with the shield 12 in the rand crease and the guide 34 in engagement with the upper. As the shoe is turned to transfer the point of operation of the cutter along the work, the upper is maintained by the operator 105 lightly in contact with the guide 34 which maintains its position in substantially concentric relation to the cutter and thus prevents the shield 12 from rubbing the surface of the upper. The guide 34, at the same time, is turned by contact with the shoe and thus facilitates the movement of the shoe without injuring the surface of the upper. It will be apparent also that by limiting the extent of projection of the shield 110 into the rand crease, the guide 34 prevents the shield from wedging into the crease in such manner as to oppose the turning movement of the shoe.

115 Should it be desired to trim in the shank to even the crease line adjacent to the end of the welt, or if for any reason it should be desired to make a deeper cut around the heel seat than is permitted by the normal position of the guide 34, sufficient pressure is 120 125 130

applied through the shoe to the guide to force back the slide 32 and thus permit the shield 12 and the cutter to project farther into the crease.

5 Having described the invention, what I claim as new and desire to secure by Letters Patent of the United States is:—

1. In a machine of the class described, the combination with a randing cutter, of a 10 shield positioned at the end of the cutter for engagement in the crease between the upper and the sole of a shoe, and means arranged with reference to said shield to protect the surface of the upper from injury through 15 contact with the shield, said means comprising a wheel arranged to be rotated by contact with the upper.

2. In a machine of the class described, the combination with a randing cutter, of a 20 shield positioned at the end of the cutter for engagement in the crease between the upper and the sole of a shoe, and a wheel arranged to roll on the upper to guide the shoe, said wheel being positioned with its 25 periphery adjacent to the edge of the shield to protect the surface of the upper from injury through contact with the shield and having a transverse peripheral contour conformable approximately to the vertical contour of the upper adjacent to the rand 30 crease.

3. In a machine of the class described, the combination with a randing cutter, of a 35 shield positioned at the end of the cutter and having a curved edge for engagement in the crease between the upper and the sole of a shoe, and a wheel arranged to engage and roll on the upper to guide the shoe, said wheel having its periphery curved 40 in substantial conformity to the curve of said edge and positioned adjacent to said edge to protect the surface of the upper from injury through contact with the shield.

45. 4. In a machine of the class described, the combination with a randing cutter, of means for guiding the shoe in its presentation to the cutter, said means comprising a wheel arranged to engage the upper of the shoe and to yield under pressure of the shoe to permit the depth of the cut to be varied.

50. 5. In a machine of the class described, the combination with a randing cutter, of a stationary shield positioned with reference to said cutter to engage the shoe in the rand crease, and a guide arranged to engage the upper of the shoe to limit the extent of projection of said shield into the

the rand crease, said guide being arranged to yield under the pressure of the shoe to 60 permit the depth of the cut to be varied.

6. In a machine of the class described, the combination with a randing cutter, of a shield positioned with reference to said cutter to engage the shoe in the rand crease, 65 and a guide arranged to engage the upper of the shoe to limit the extent of projection of said shield into the rand crease, said guide comprising a wheel arranged to be rotated by contact with the shoe and to 70 yield under the pressure of the shoe to permit the depth of the cut to be varied.

7. In a machine of the class described, the combination with a rotary cutter, of a shield positioned at the end of the cutter for engagement in the crease between the upper and the sole of a shoe, and a guide arranged to engage the upper to limit the extent of projection of the shield into said crease, 75 said guide having an edge of substantially the same contour as the edge of the shield and being mounted for yielding movement in a plane substantially parallel to the plane of the shield.

8. In a machine of the class described, 80 the combination with a rotary cutter, of a shield positioned at the end of the cutter for engagement in the crease between the upper and the sole of a shoe, said shield having an edge curved in substantially concentric 85 relation to the cutter, a guide arranged to engage the upper of the shoe, said guide comprising a wheel of substantially the same radius as the curve of said shield and arranged to rotate as the work is fed past 90 it, and means for positioning the guide normally with its peripheral edge adjacent to the curved edge of the shield.

9. In a machine of the class described, 95 the combination with a rotary cutter, of a shield positioned at the end of the cutter for engagement in the crease between the upper and the sole of a shoe, a support mounted for movement in a plane substantially parallel to the plane of said shield, a 100 guide mounted for rotation on said support and arranged to engage the upper of the shoe adjacent to the shield, and a spring arranged to position said support normally with the edge of the guide adjacent to the 105 edge of the shield and to yield under pressure of the shoe to permit the depth of the cut to be varied.

In testimony whereof I have signed my name to this specification.

FRANK H. WARREN.
